UNITED STATES PATENT OFFICE.

OSCAR HOFFMANN, OF NUEREMBERG, GERMANY.

SAMPLE OR CONVEYING BAG.

SPECIFICATION forming part of Letters Patent No. 643,291, dated February 13, 1900.

Application filed July 18, 1899. Serial No. 724,273. (No model.)

To all whom it may concern:

Be it known that I, OSCAR HOFFMANN, a subject of the Emperor of Germany, and a resident of Nuremberg, Bavaria, in the Empire of Germany, have invented certain new and useful Improvements in Sample or Conveying Bags, of which the following is a specification.

This invention has for its object a sample-bag or conveying-bag formed of paper, 10 strengthened by linings or the like of some suitable fabric or material, which bag is extremely suitable for conveying pulverulent materials, such as cement, meal, or the like. This is attained by the bag being made in one 15 piece, so that the bottom seam is entirely dispensed with, while the side seams are formed by folding and gumming together the encountering edges and strengthening the seam at the points of connection by the insertion of 20 wire clamps. The latter serve at the same time for attaching carrying-bands which run up both sides of the bag and serve also as distributors of the load when the bag is conveyed and also allow of the bag being conveniently 25 handled.

In the accompanying drawings a representation of this improved bag is shown, which will now be more particularly described.

Figure 1 is a vertical section of the bag on 30 the lines A B and C D of Fig. 3; Fig. 2, a view in perspective of the whole arrangement, and Fig. 3 a cross-section of the connection.

The bag is made by a sheet of paper, combined with a lining or the like of fabric, being 35 bent upward from its center to both sides, so that thus a bottom surface *h* is formed, and the bent-up surfaces form two sides *a* and *b* of the bag. By bending inward a portion of the said sides *a* *b* the narrow or remaining 40 sides *c* *d* of the bag are formed, the encountering edges of which are overlapped or folded together in the manner shown in Fig. 3, and, if necessary, gummed together, so that any 45 escape at these points of the material or substance contained in the bag is prevented with certainty. The projecting flaps or lugs *e*, formed on the bottom by the folding of the side walls *a* *b* *c* *d*, are bent upward and con-

nected with the narrow sides *e* *d* of the bag by means of wire clamps or staples *f*. Further, a sure connection of these flaps *e* with the narrow sides, which also affords an increased resistance to bursting at the most susceptible places of the bag, is obtained by passing one of the ends of carrying-bands *g* 50 in several coils through suitable successive holes in the flaps *e* and in the side seams formed by the folding in the manner shown in Fig. 1. These carrying-bands *g*, the loose ends of which are provided with handles *o* to 55 afford a better hold, as shown in the drawings, are passed along the side seams and attached thereto by means of wire clamps or staples *f*, inserted through the latter, whereby the pull resulting when the sack or bag is carried is conveyed to larger surfaces and any 60 tearing or bursting of the bag is, as far as possible, suitably prevented.

After the bag has been filled it is closed by the upper parts of the walls being folded over 70 a sheet of cardboard laid therein and held closed by the bag being bound with bands *i*, inserted in the fold or connection of the side seams.

The carrying-bands may also be sewed on 75 or attached in any other suitable manner instead of being fixed with clasps.

Having now particularly described and ascertained the nature of my said invention and in what manner the same is to be performed, 80 I declare that what I claim is—

As an article of manufacture, a sample or conveying bag comprising a single sheet of material folded upon itself with inwardly-turned overlapping side edges and bottom 85 folds or flaps turned upwardly against said overlapping edges, fastening means securing said flaps and overlapping portions, and carrying-bands held by said fastening means, substantially as described. 90

In witness whereof I have hereunto set my hand in presence of two witnesses.

OSCAR HOFFMANN.
